UNITED STATES PATENT OFFICE.

CARL HUBE, OF SAN FRANCISCO, CALIFORNIA.

SAFETY-GUARD FOR ROTARY STICKER-HEADS.

1,286,329.

Specification of Letters Patent.

Patented Dec. 3, 1918.

Application filed May 29, 1918. Serial No. 238,787.

To all whom it may concern:

Be it known that I, CARL HUBE, a citizen of the United States, residing in the city and county of San Francisco and State of California, have invented a new and useful Improvement in Safety-Guards for Rotary Sticker-Heads, of which the following is a full, clear, and exact description, such as will enable others skilled in the art to which it appertains to make and use the same.

My invention relates to improvements in safety guards for rotary sticker heads wherein an adjustable chip breaker operates to guard that side and top of the cutter head adjacent the operator and also to retain uncut portions of lumber, passing through the sticker, firmly upon the table of the machine.

The primary object of the present invention is to provide an improved, simple and effective guard for rotary sticker heads and the like; that may be easily and simply adjusted to guard an operator from injury and to retain the lumber being cut.

A still further object is to provide an improved chip breaker and guard of the character described which may be adjusted to form a guide for lumber being cut.

A still further object of the invention is to provide a guard adjustable to cutter heads of various diameters.

I accomplish these several objects by means of the device disclosed in the drawings forming a part of the present specification wherein like characters of reference are used to designate similar parts throughout the said specification and drawings, and in which—

Figure 1 is a plan view of a portion of a sticker table, disclosing the cutter head and the guard attached thereto;

Fig. 2 is a front elevation of Fig. 1 with the table shown in section;

Fig. 3 is a left hand elevation of Fig. 2 with the table portion shown in section; and

Fig. 4 is a left hand elevation of Fig. 3 with the upper portion of the cutter head and the cutting blades removed.

Referring to the drawings the numeral 1 is used to designate a table of a sticker machine and 2 the cutter head rotated by a shaft 3 and carrying cutter blades 4.

An arm 6 is pivotally mounted upon the table 1 as at 7 and is provided with an arcuate slotted extension 8 through which

passes a securing bolt 9 engaged by a suitable thumb nut 11.

The arm 6 is moved upon its pivot to adjust the same relatively to the cutter head 2 and when properly adjusted is securely held in position by tightening the thumb nut 11 on the bolt 9.

The arm 6 terminates in an arcuate portion 12 having a vertically disposed extension 14 to serve as a chip breaker.

The extension 14 is provided with a vertically disposed groove 16 within which is slidably mounted a bolt 17 provided with a thumb nut 18.

An offset flexible or spring member 21 is provided with an arcuate extension 22, having an arcuate slot 23 therein, arranged to extend over the cutter blades 4 and adjacent the cutter head 2, which hold said blades 4, as disclosed in Fig. 1 of the drawings. The opposite end of the member 21 is provided with a horizontally slotted vertical extension 24 which is engaged by the bolt 17 and the thumb nut 18 therefor to rigidly secure the said member 21 in position.

In order to prevent the member 21 from rotating about the bolt 17 a series of lugs 26 are formed integral with the vertical extension 24 and parallel with the groove 16 therein one of which lugs 26 rests under the end of the flexible member 21 to prevent the arcuate end 22 thereof from being raised when an upward pressure is brought to bear on said arcuate portion 22 in a manner hereinafter more fully set forth.

A bolt 27, provided with a thumb 28, passes through the arcuate slot 23 in the arcuate portion 22 of the flexible member 21, and also through a slot 31 in a short plate 95 or lug 32 which carries an arcuate block 33 having its under surface curved upwardly near the ends thereof.

By referring to Fig. 1 it will be observed that by means of this arrangement the arcuate block 33 may be adjusted radially and circumferentially relatively to the cutter head 2.

The operation is as follows:

By loosening the thumb nut 11 on the bolt 9 the arm 6 may be adjusted to bring the edge of the vertical extension 14 adjacent to the circular path described by the rotation of the cutter blades 4 so that said edge will serve as a chip breaker. This adjust-

ment is disclosed in Fig. 1 of the drawings and operates to accommodate cutter heads of various diameter within the range of the machine.

5 The flexible offset member 21 is adjusted by loosening the thumb nut 18 and bolt 17 and moving the said member 21 vertically with its end resting on the proper lug 26, until the arcuate end 22 of the member 21 10 rests at a proper height which will bring the lower surface of the arcuate block 33 a distance above the table 1 slightly less than the thickness of the lumber to be cut.

The lower surface of the block 33 will 15 then be slightly lower than the upper edges or tops of the cutter blades 4 as disclosed in Fig. 3 of the drawings.

The chip breaker edge of the vertical extension 14 of the arm 6 is adjusted in a 20 longitudinal line, relatively to the table 1 and the direction to be taken by the lumber to be cut, so that said edge will serve as a guide when inserting said lumber. The stick of lumber is indicated in dotted lines 25 in Fig. 1 of the drawings.

As the arcuate block is adjusted so as to leave a space between its lower surface and the surface of the table 1 slightly less than the thickness of the lumber to be cut it is 30 evident that as the said lumber is inserted under the curved lower end of said block 33 an upward pressure will be exerted on the arcuate portion 22 of the flexible member 21 which pressure would tend to rotate the 35 said member 21 about the pivot as represented by bolt 16 in the vertical extension 14 of the arm 6.

But, such rotation is prevented by the end 40 of the lug 26 which rests under the end 21 of the said flexible member, and the resulting upward pressure places the flexible member 21 under a tension, the reaction of said tension operating to hold the lumber being 45 cut firmly onto the table 1.

45 It is obvious from the foregoing that I have provided an improved guard for sticker cutter heads that will effectively guard the operator from injury to hands while passing lumber through the machine 50 as the arcuate block 33 and arcuate portion 22 of the flexible member 21 effectively cover and screen the revolving knives or blades 4.

It is also evident that the device may be 55 adjusted to various positions to suitably accommodate the thickness of lumber being cut and also various diameters of cutter heads.

Having thus described my invention what I claim as new and desire to secure by Letters Patent is—

60 1. A safety guard for rotary cutter heads of sticker machines comprising an arm pivotally mounted adjacent the head and terminating in an arcuate chip breaker; an adjustable flexible member secured to the chip

breaker and arranged to extend over the rotating head; and means adjustably mounted on the flexible member to engage and retain on the sticker table, lumber being operated upon by the rotary cutter.

70 2. A safety guard for rotary cutter heads of sticker machines comprising an arm pivotally mounted on the table of the machine and terminating in an arcuate upright extension adjacent the cutter head to form a 75 chip breaker, said chip breaker having a vertically disposed groove in the side thereof adjacent the cutter head; an arcuate offset member slidably mounted within the groove and extending over the rotating blades of the cutter head at one side of said head; an arcuate block adjustably mounted upon the extension to engage and retain the uncut portion of lumber being operated upon by the cutter head.

80 3. A safety guard for rotary cutter heads of sticker machines comprising an arm pivotally mounted on the table of the machine and terminating in an arcuate upright extension adjacent the cutter head to form a chip 85 breaker, said chip breaker having a vertically disposed groove in the side thereof adjacent the cutter head; an arcuate offset member slidably mounted within the groove and extending over the rotating blades of the cutter head at one side of said head; an arcuate block adjustably mounted upon the extension to engage and retain the uncut portion of lumber being operated upon by the cutter head; and means for preventing the rotation 90 of the arcuate offset member around its securing point on the chip breaker.

95 4. A safety guard for rotary cutter heads of sticker machines comprising an arm pivotally mounted on the table of the machine 105 and terminating in an arcuate upright extension adjacent the cutter head to form a chip breaker, said chip breaker having a vertically disposed groove in the side thereof adjacent the cutter head; an arcuate offset 110 member slidably mounted within the groove and extending over the rotating blades of the cutter head at one side of said head; an arcuate block adjustably mounted upon the extension to engage and retain the uncut 115 portion of lumber being operated upon by the cutter head; and a series of lugs formed integral with the side of the chip breaker adjacent the cutter head to engage the end of the arcuate offset member to prevent the movement thereof.

120 5. A safety guard for rotary cutter heads of sticker machines and the like comprising an arm pivotally mounted upon the table of the machine and having a vertically disposed 125 arcuate extension adjacent the cutter head to form a chip breaker, said extension being provided with a vertically disposed groove; a series of lugs formed parallel with the groove and integral with the chip breaker; 130

- a flexible member engaging one of the lugs to prevent an upward movement of the outer end of said member and having an arcuate extension arranged over the knives of the cutter head; means slidably mounted within the groove to engage the flexible member and rigidly secure same to the chip breaker; and an arcuate block adjustably mounted upon the arcuate portion of the flexible member 5 and extending beyond the rotating knives of the cutter head to engage and retain the uncut portion of lumber on the sticker table.
6. A safety guard for rotary cutter heads of sticker machines and the like comprising an arm pivotally mounted upon the table of the machine and having a vertically disposed arcuate extension adjacent the cutter head to form a chip breaker, said extension being provided with a vertically disposed 10 groove; a series of lugs formed parallel with the groove and integral with the chip breaker; a flexible member engaging one of the lugs to prevent an upward movement of the outer end of said member and having an arcuate extension arranged over the knives of the cutter head; means slidably mounted within the groove to engage the flexible member and rigidly secure same to the chip breaker; and an arcuate block adjustably mounted upon the arcuate portion 15 of the flexible member and extending beyond the rotating knives of the cutter head to engage and retain the uncut portion of lumber on the sticker table; and means for adjusting the arm and chip breaker relatively to the cutter head.
7. In witness whereof I have hereunto set my signature.

CARL HUBE.
